UNITED STATES PATENT OFFICE.

ALPHEUS C. McNICHOL, OF NOKOMIS, SASKATCHEWAN, CANADA.

HOUSE-MOVING DEVICE.

1,261,142.

Specification of Letters Patent. Patented Apr. 2, 1918.

Application filed May 28, 1917. Serial No. 171,479.

To all whom it may concern:

Be it known that I, ALPHEUS C. McNICHOL, a citizen of the Dominion of Canada, residing at Nokomis, in the Province of 5 Saskatchewan, Dominion of Canada, have invented certain new and useful Improvements in House-Moving Devices; and I do hereby declare the following to be a full, clear, and exact description of the invention, 10 such as will enable others skilled in the art to which it appertains to make and use the same.

This invention relates to improvements in devices for moving portable granaries, 15 houses, or other buildings.

One object of the present invention is to provide a device of this character which can be operated to move a building without the aid of the large number of men and animals 20 usually employed with previous devices of this nature.

Another object is to provide a device of this character which can be more quickly and efficiently placed under the edges of a 25 building, and by means of which the building can be raised into position for moving.

A further object is to provide a novel shoe which is used in connection with the jacks of the device for the purpose of preventing 30 the jacks from digging into the ground as the building is moved.

Other objects and advantages will be apparent from the following description when taken in connection with the accompanying 35 drawing.

In the drawing:

Figure 1 is a side elevation of a portion of a building mounted on my improved trucks or jacks.

40 Fig. 2 is an enlarged side elevation of one of the trucks and skid connected thereto.

Fig. 3 is a side elevation of the truck looking from the opposite side from that of Fig. 2.

45 Fig. 4 is a front elevation of the truck.

Fig. 5 is a top plan view of the skid.

Referring particularly to the accompanying drawings 10 represents an upright having a vertical elongated slot 11 formed therethrough in the lower portion thereof. One side wall of this slot is formed with a series of rack teeth 12. A forwardly extending horizontal foot 13 is formed on the lower end of this upright, as shown. A pair of inclined braces 14 are connected to the upper 55 end of the upright and carry on their lower

ends the feet 15 similar to the foot 13, and in parallel relation to each other and to the said foot 13. A second upright is disposed behind the first one, and in parallel relation 60 thereto, said second upright being formed, in its lower portion with an elongated slot 16, one wall of which is formed with rack teeth 17. A shaft 18 is disposed through the slots of the uprights and carries on its 65 end portions the pinions 19 and 20, respectively which mesh with the respective rack teeth 12 and 17 of the uprights. On the end of the shaft, adjacent the pinion 20 there is secured a worm wheel or pinion 21 which 70 meshes with a worm shaft 22 mounted in brackets 23 on the upright 10'. The end of this shaft is provided with a crank handle by means of which said shaft may be rotated. A ratchet wheel 24 is rigidly secured 75 to the said worm shaft and is arranged to be engaged by the pawl 25 carried by the lever 26 which is loosely mounted on said shaft. Braces 27 connect the upright 10' with the lower ends of the inclined braces, as clearly 80 shown in the drawings. Secured on the said feet of the upright 10 and the braces 14, is a platform 28, and on this platform one edge of the bottom of the granary 29, or other building is adapted to rest, while being 85 moved from one place to another. On the before-mentioned shaft there is mounted a large and broad threaded wheel which is adapted to engage on the ground to move the building, this wheel being represented 90 by the reference character 30.

Rotatably mounted between the upright 10 and one of the inclined braces, is a winding drum 31 on which is wound one end of a chain 32. A crank handle 33 and pawl 95 and ratchet means 34 are provided for the purpose of rotating said drum.

The chain 32 is passed under the house, the ends being connected to and wound on the drums 31, whereby the two trucks will 100 be held in proper position at the sides of the house and thus efficiently support and carry the house.

From the drawing it will be understood that there are two of the devices above described, one for each side of the building to be moved. Disposed beneath the front of the house is a shoe, designated as a whole by the reference character A. This shoe includes an upper plate 35, a lower plate 36, 110 which forms the shoe proper or runner, and the connecting links 36' which are pivotally

connected between said plates. The rear end of the lower plate is connected to the forward ends of the platforms of the two trucks by means of the chains 37, while the forward end of the upper plate is reduced, as at 38 and disposed through an opening 39 in the upturned forward end of the lower plate. This reduced end is adapted to be connected to draft animals.

10 In the operation of the device, the trucks are placed at the sides of the building slightly to the rear of the middle thereof, and the shoe under the front of the house. The worm shaft is then rotated to turn the 15 shaft which carries the wheel whereby the engagement of the pinions of the shaft will ride up on the racks of the uprights and lift the house above its foundation, said house thus being supported on the platforms.

20 The animals are then hitched to the forward end of the upper plate of the shoe. Forward pull on the upper plate will swing the same upwardly on the connecting links and raise the front end of the house. This end 25 will then be supported on the shoe and the house prevented from tilting downwardly in the front with the result that the forward ends of the platforms of the trucks are prevented from digging into the ground 30 over which the trucks are moving.

It will be noted that when the upper plate of the shoe is swung upwardly and forwardly to support the front end of the house, the wider portion engages with a pair 35 of upstanding stop lugs 40 carried by the lower plate, thereby preventing said upper plate from moving forwardly and again let-

ting the house tilt downwardly. The upper ends of the links swing forwardly past the lower ends so that there is no danger of 40 backward movement. The forward end of the house thus slides on this shoe, while the remainder of the house is supported on the wheeled trucks.

What is claimed is:

1. A house moving device including a pair of wheeled trucks for supporting the sides of a house, and a shoe for supporting the front end of the house and connected to said trucks, said shoe including a house 50 engaging member and a ground engaging member, and movably connected spacing members connecting the said house and ground engaging members.

2. A house moving device including supporting wheeled trucks, and a shoe for supporting the front end of a house, said shoe including a lower or ground engaging plate, an upper or house engaging plate, links pivotally connecting the plates, the forward 60 end of the lower plate being formed with an opening, the forward end of the upper plate being reduced and engaged in said opening, said reduced end being adapted for attachment of draft animals, stop lugs on the lower plate for engagement by the upper plate, and connections between the lower plate and the said trucks.

In testimony whereof, I affix my signature, in the presence of two witnesses.

ALPHEUS C. McNICHOL.

Witnesses:

GEO. W. BRAITHWAITE,
C. L. CAMPBELL.
